UNITED STATES PATENT OFFICE.

PAUL G. SWARS, OF PITTSBURGH, PENNSYLVANIA, ASSIGNOR TO WESTINGHOUSE ELECTRIC & MANUFACTURING COMPANY, A CORPORATION OF PENNSYLVANIA.

CLAMP FOR TROLLEY CONDUCTORS.

Application filed December 7, 1923. Serial No. 679,068.

To all whom it may concern:

Be it known that I, PAUL G. SWARS, a citizen of the United States, and a resident of Pittsburgh, in the county of Allegheny and 5 State of Pennsylvania, have invented a new and useful Improvement in Clamps for Trolley Conductors, of which the following is a specification.

My invention relates to overhead trolley 10 devices, such as frogs, cross-overs, switches, etc., and particularly to the means employed for securing trolley conductors to such devices.

One object of my invention is to provide 15 an overhead trolley device and means for clamping trolley conductors thereto that shall be inexpensive to manufacture and which may be readily and quickly assembled.

Another object of my invention is to provide 20 an overhead trolley device to which trolley conductors may be secured with a minimum amount of effort and from which they may be removed without completely separating the parts of the device.

25 My invention embodies a clamping member provided with trolley-conductor gripping portions at one end and a bearing portion at the other end adapted to co-operate with similar portions of an overhead trolley 30 device, whereby trolley conductors may be readily clamped between the conductor-gripping portions and be securely fastened in position.

In the accompanying drawing, Figure 1 is 35 a view in side elevation, of my invention as applied to a trolley frog, the ends of the frog being broken away.

Fig. 2 is a top plan view of the portion of 40 the trolley frog shown in Figure 1, without the clamping member;

Fig. 3 is a top plan view and Fig. 4 is a bottom plan view of the clamping member included in Fig. 1.

Fig. 5 is an end view of the clamping 45 member taken from the end on which the projecting portions adapted to grip the trolley conductors are located.

In order that my invention may be more 50 fully understood, I have shown it as applied to a trolley-conductor frog or turn-out, having a body portion 1 provided with ribs or runners 2 for guiding trolley wheels. The body member is provided, at each side, with supporting lugs 3 and 4, to which guy wires, 55 (not shown), or other supporting means may

be attached. Depressions 5 are located in the top of the body member for receiving trolley conductors 6. On top of the body member 1, near its central portion, are located rough or threaded gripping portions 7 and 8 for gripping the trolley conductors 6.

In order that the trolley conductors may be properly clamped to the body member, I provide a clamping member 9 having gripping portions 10 and 11 at one end that are 60 adapted to bear against the trolley conductors 6, preferably at locations opposite the roughened portions 7 and 8 of the body member. The other end of the clamping member 9 is provided with a projection or 65 boss 12 that is adapted to enter a recess or recessed boss 13 in the body member, and thereby locate the clamping member in position, and assist it in clamping the trolley conductors.

A single fastening device, such as a bolt or a screw-threaded stud 14 and a wing-nut 15, may be employed for securing the clamping member in position and forcing it 70 against the trolley conductors 6.

In assembling the device, the clamping member 9 is first loosely secured to the body member 1 by means of the screw threaded stud 14 and the wing-nut 15. After that, the trolley conductors 6 are placed in such position as to rest in the recesses 5 and the rough or screw-threaded gripping portions 7 and 8 of the body member 1. Then the wing-nut 15 is tightened on the screw-threaded stud 14, and pressure is thereby 75 brought to bear on the central portion of the clamping member 1. Inasmuch as the stud 14, at one end of the clamping member 9, fits into the recess 13 and bears against the body member 1, the gripping portions 10 and 11 at the other end of the clamping member 80 will be forced against the trolley conductors 6 and securely hold them in position.

I desire it to be understood that, while I have shown and described a specific form 85 of device, such form may be varied within considerable limits without departing from the spirit and scope of my invention.

I claim as my invention:

1. A conductor-supporting device comprising a body member having portions adapted to grip trolley conductors and provided with a bearing portion, a clamping member having conductor-gripping portions at one end and provided, at its other end, 105

with a bearing portion adapted to co-operate with the bearing portion on the body member, and fastening means passing through the central portion of the clamping member 5 for securing it to the body member.

2. A conductor-supporting device comprising a body member having portions adapted to grip trolley conductors and provided with a recess, a clamping member 10 having conductor-gripping portions at one end and provided, at its other end, with a pivoting stud adapted to fit into the recess in the body member, and fastening means passing through the central portion of the 15 clamping member for securing it to the body member.

3. A conductor-supporting device comprising a body member having portions adapted to grip trolley conductors and provided with a recessed boss, a clamping member 20 having conductor-gripping portions at one end and provided, at its other end, with a pivot stud adapted to fit into the recess in said boss, and a bolt that passes through 25 the central portion of the clamping member for securing it to the body member.

4. A conductor-supporting device comprising a body member having portions adapted to grip trolley conductors and provided 30 with a bearing portion, a clamping member having conductor-gripping portions at one end and provided, at its other end, with a bearing portion adapted to co-operate 35 with the bearing portion on the body member, and a screw-threaded stud and nut located in the middle portion of the clamping

member for securing it to the body member and thereby clamping the trolley conductors.

5. In a conductor-supporting device, the combination with a body member provided 40 with grooves for trolley conductors, of a clamping member provided with a bearing portion at one end and with conductor-gripping portions at its other end, and means located near the middle portion of 45 the clamping member for fastening it to the body member and clamping the trolley conductors.

6. A clamping member for clamping trolley conductors to overhead devices comprising 50 an elongated member provided with projections at one end for gripping the trolley conductors and with a bearing portion at its other end adapted to co-operate with a bearing portion on the overhead device and pivotally support the clamping member and having a hole near its middle portion through which fastening means may pass.

7. A clamping member for clamping trolley conductors to overhead devices comprising 55 an elongated member provided with projections at one end for gripping the trolley conductors and with a projection at its other end adapted to enter a recess in the overhead device and pivotally support the clamping member and having a single hole near its middle portion through which fastening means may pass.

In testimony whereof, I have hereunto 60 subscribed my name this 28th day of November, 1923.

PAUL G. SWARS.
